(57) **CLAIM**

The ornamental design for a garment, as shown and described.

DESCRIPTION

FIG. 1 is a front perspective view of a garment showing our new design according to a first embodiment.

FIG. 2 is a front view of our new design shown in FIG. 1.

FIG. 3 is a rear view of our new design shown in FIG. 1.

FIG. 4 is a right-side view of our new design shown in FIG. 1.

FIG. 5 is a left-side view of our new design shown in FIG. 1.

FIG. 6 is a top view of our new design shown in FIG. 1.

FIG. 7 is a bottom view of our new design shown in FIG. 1.

FIG. 8 is a front perspective view of our new design shown in FIG. 1 when in use.

FIG. 9 is a cross-sectional view taken along line 9-9 of FIG. 4.

FIG. 10 is a cross-sectional view taken along line 10-10 of FIG. 4.

FIG. 11 is a cross-sectional view taken along line 11-11 of FIG. 2.

FIG. 12 is a front perspective view of a garment showing our new design according to a second embodiment.

FIG. 13 is a front view of our new design shown in FIG. 12.

FIG. 14 is a rear view of our new design shown in FIG. 12.

FIG. 15 is a right-side view of our new design shown in FIG. 12.

FIG. 16 is a left-side view of our new design shown in FIG. 12.

FIG. 17 is a top view of our new design shown in FIG. 12.

FIG. 18 is a bottom view of our new design shown in FIG. 12.

FIG. 19 is a front perspective view of our new design shown in FIG. 12 when in use.

FIG. 20 is a cross-sectional view taken along line 20-20 of FIG. 15.

FIG. 21 is a cross-sectional view taken along line 21-21 of FIG. 15; and,

FIG. 22 is a cross-sectional view taken along line 22-22 of FIG. 13.

The short broken lines showing elements of the garment in the drawings illustrate features of the article of manufacture that form no part of the claimed design. The human figure rendered in short broken lines in FIGS. 8 and 19 illustrates environmental subject matter intended to assist in showing how the design appears when in use and forms no part of the claim.
